SAFETYPIN FOR SHOULDER STRAPS

Helen Payes, Brooklyn, N. Y.

Application October 24, 1938, Serial No. 236,623

4 Claims. (Cl. 24—73)

This invention relates to new and useful improvements in a triangular safety pin for holding garment straps on shoulders.

More specifically, the invention proposes the construction of a triangular safety pin which is adapted to have one of its corners engaged upon the shoulder seam of an outer garment while the shoulder strap of an inner garment passes through the center thereof for holding said shoulder strap in position upon one's shoulder and in fixed relation with said seam.

Still further the invention proposes to construct the safety pin from a piece of wire and to provide one of its ends with a hook into which the free end of said wire may engage for holding the pin in its closed position and prevent said shoulder strap from accidentally disengaging therefrom.

Still further the invention proposes the provision of a clip on one side of said hook and beneath which said strap may be forced for holding the free end of said wire from accidentally disengaging from said hook.

For further comprehension of the invention, and of the objects and advantages thereof, reference will be had to the following description and accompanying drawing, and to the appended claims in which the various novel features of the invention are more particularly set forth.

30 In the accompanying drawing forming a material part of this disclosure:

Fig. 1 illustrates a safety pin according to this invention in position for holding a shoulder strap upon one's shoulder.

35 Fig. 2 is an enlarged detailed view of a portion of Fig. 1 but showing the pin in its open position.

Fig. 3 is a sectional view taken on the line 3—3 of Fig. 2.

40 Fig. 4 is a view similar to Fig. 2 but illustrating a modification of the invention.

Fig. 5 is a sectional view taken on the line 5—5 of Fig. 4.

Fig. 6 is a view looking in the direction of the 45 line 6—6 of Fig. 4.

The triangular safety pin for holding garment straps on a shoulder is to be used in conjunction with an outer garment 10 having a shoulder seam 10^a and an inner garment 11 having a 50 shoulder strap 11^a which is adapted to pass over one's shoulder and which has its ends attached to the top edges of the inner garment 11.

The triangular safety pin comprises a length of wire 12 having a horizontal bottom portion 12^a, an 55 upwardly and inwardly inclined side portion 12^b

continuing from one end of the bottom portion 12^a, and a downwardly and outwardly inclined side portion 12^c continuing from the top end of the side portion 12^b. The free end of the latter side portion 12^c has a piercing point 13 to facilitate the passing of the side portion 12^c through the material of the outer garment 10 at a point along the shoulder seam 10^a. A hook 14 is mounted on the free end of the horizontal portion 12^a for holding the strap 11^a from slipping off thereof and to receive and hold the piercing point 13 to close the pin as shown in Fig. 1.

The junction of the side portions 12^b and 12^c is arranged above the center of the horizontal portion 12^a in a manner so that the bottom portion 12^a and the side portions 12^b and 12^c form an equilateral triangle. The junction of the sides 12^b and 12^c are formed with an annular looped portion 15 which is adapted to engage around the seam 10^a when the piercing point 13 is passed through the material of the outer garment 10 on either side of the said seam.

The operation of this device is as follows:

The piercing point 13 is engaged through the material of the outer garment 10 on either side of the seam 10^a and the downwardly and outwardly inclined side portion 12^c is passed through the said material until the loop portion 15 engages around the seam 10^a. This is done in a proper position along the length of the seam 10^a so as to support the shoulder strap 11^a in a position in which the wearer is accustomed to positioning the shoulder strap. The shoulder strap 11^a is then passed through the open side of the pin 12 between the piercing point 13 and the hook 14. The piercing point 13 is then engaged into the hook 14 for closing the safety pin 12 to prevent the shoulder strap 11^a from being accidentally disengaged therefrom so as to support the shoulder strap in its closed position.

According to the modification shown in Figs. 4—6 the safety pin 12' is formed with side portions 12^{bb} and 12^{cc} of a concaved shape and a horizontal bottom portion 12^a having its center point arranged below the junction of the sides 12^{bb} and 12^{cc} to form an equilateral triangle having two concave sides. The hook 14' is provided with a clip 17 having one of its edges 17^a fixedly attached to the adjacent face of the hook 14' and the other of its ends 17^b turned outward with relation to the adjacent face of the hook 14' so that the shoulder strap 11^a may be engaged between the adjacent faces of the clip 17 and the hook 14' and across the mouth of the hook 14' for holding the piercing

point 13 from accidentally disengaging therefrom.

After the piercing point 13 has been passed through the material of the outer garment 10 and engaged with the hook 14' to hold the safety pin in its closed position, the edge portion of the shoulder strap 11^a adjacent the clip 17 is engaged between the adjacent faces of the clip 17 and the hook 14' for holding the piercing point 13 in position within the face of the hook 14'. In other respects this form of the invention is similar to the previous form and similar parts may be identified by corresponding reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A triangular safety pin for holding garment straps on a shoulder, comprising a length of wire having a horizontal bottom portion, an upwardly and inwardly inclined side portion continuing from one end of said bottom portion and a downwardly and outwardly inclined side portion continuing from the top end of said side portion, the free end of said latter side portion having a piercing point, and a hook on the free end of said horizontal portion for holding a strap from slipping therefrom and being adapted to receive and hold said piercing point to close said pin, and means on said hook for holding an edge portion of said strap across the mouth opening of said hook in the closed position of said pin for preventing said piercing point from accidentally disengaging said hook.

2. A triangular safety pin for holding garment straps on a shoulder, comprising a length of wire having a horizontal bottom portion, an upwardly and inwardly inclined side portion continuing from one end of said bottom portion and a downwardly and outwardly inclined side portion continuing from the top end of said side portion, the free end of said latter side portion having a piercing point, and a hook on the free end of said horizontal portion for holding a strap from slipping therefrom and being adapted to receive and

hold said piercing point to close said pin, and means in the closed position of said pin for preventing said piercing point from accidentally disengaging said hook, comprising a clip on said hook for engaging and holding an edge portion of said strap and holding a portion of said strap across the mouth end of said hook for holding the piercing point from accidentally disengaging therefrom.

3. A triangular safety pin for holding garment straps on a shoulder, comprising a length of wire having a horizontal bottom portion, an upwardly and inwardly inclined side portion continuing from one end of said bottom portion and a downwardly and outwardly inclined side portion continuing from the top end of said side portion, the free end of said latter side portion having a piercing point, and a hook on the free end of said horizontal portion for holding a strap from slipping therefrom and being adapted to receive and hold said piercing point to close said pin, and means in the closed position of said pin for preventing said piercing point from accidentally disengaging said hook, comprising a clip on said hook for engaging and holding an edge portion of said strap and holding a portion of said strap across the mouth end of said hook for holding the piercing point from accidentally disengaging therefrom, said clip comprises a strip of material having one of its edges fixedly attached to the adjacent face of said hook and the other of its faces turned outward with relation to said hook so that said strap may be easily passed beneath said clip.

4. A safety pin for holding garment straps, comprising a length of wire bent into a triangular pin having its ends adjacent one another so that a shoulder strap may be passed therein, a piercing point formed on one end of said length of wire to permit said pin to be engaged on one's outer garment in the vicinity of the shoulder seam, a hook mounted on the other end of said length of wire, said piercing point being engageable into said hook for closing said pin to prevent said shoulder strap from disengaging therefrom, and a clip mounted on one side of said hook for engaging and holding an edge portion of said strap in a position in which a portion thereof will engage across the mouth of said hook for holding the piercing point from accidentally disengaging therefrom.

HELEN PAYES.
